CLAIM

The ornamental design for a beverage container, as shown and described.

DESCRIPTION

FIG. 1 is a perspective view of a beverage container showing my new design;

FIG. 2 is a front view, the rear view being the same;

FIG. 3 is a left side view, the right side view being the same;

FIG. 4 is a top plan view thereof; and,

FIG. 5 is a bottom plan view thereof.

The broken lines in the drawings depict portions of the beverage container that form no part of the claimed design.
